UNITED STATES PATENT OFFICE.

JOHN L. SMITH, OF WINSTON-SALEM, NORTH CAROLINA.

SEAT FOR BARBER CHAIRS AND THE LIKE.

Application filed October 27, 1926. Serial No. 144,531.

This invention relates to reclining chairs, such as used by physicians, dentists, and barbers, and more especially to barber chairs, wherein said chair is provided with a folding 5 stool, which is adapted to be secured to the chair, for use by the operator, while the chair is unoccupied by a patient or customer.

Heretofore, in barber shops, it has been customary for barbers, whose chairs are not 10 occupied by a customer to take seats in some portion of the shop, thus making it necessary for all other barbers to rise and take their positions at their respective chairs when a customer enters the shop. By use of my invention, 15 barbers may remain seated at their respective chairs, when said chairs are not occupied by a customer, so that when a customer enters, each barber will be stationed at his chair ready to wait upon the customer, 20 regardless of which chair the customer may select.

Having stated some of the objects of my invention, other objects will appear as the description proceeds.

25 In the drawings, I have shown a preferred embodiment of my invention, in which—

Figure 1 is a perspective view of a barber chair with my invention attached thereto:

Figure 2 is a side elevation of my invention 30 and a part of a barber chair, showing the invention attached to the barber chair:

Figure 3 is a plan view of Figure 2, showing the manner in which the stool folds underneath the chair:

Figure 4 is an enlarged detailed perspective view of the hinge and associated parts 35 for securing the stool to the barber chair.

A brief description of the drawings, having 40 been given, a detailed description will now follow, in which like reference characters indicate corresponding parts throughout the drawings.

The numeral 10 indicates the upright portion 45 of the base of a barber chair, which has a shaft 11 adapted to be adjusted vertically within the base 10, as is conventional in all barber chairs. Secured to the top of the member 11 is the frame work 12, which is adapted to have mounted thereon, the seat 50 13, the back 14, and the arms 15. The portion 12 has the hub portion 16 for engaging the shaft 11 and extending outwardly from this hub portion 16, are the arms 17, which are integral with the ring 19, forming the outer surface of the member 12.

55 My invention is adapted to be secured

to one of the arms 17, by means of the member 20, fitting underneath one of the arms 17 and against the inner face of the ring 19. This member 20 has a projection 22, which 60 extends upwardly from the portion 21 and then parallel with the portion 21. A set screw 23, threadably pierces the member 21 and presses against a plate 24, which plate presses against the lower side of one of the 65 arms 17. The member 20 has another upwardly projecting portion 25, which fits into a cavity 26, as is shown in Figure 2. The lower portion of the member 20 has a slot 27 therein, and a bolt 28 passes through the 70 lower portion of the member 20 and through said slot, said bolt 28 being adapted to pierce the upper end of the member 30. The member 30 has a projection 31 thereon, which has a vertical hole therethrough, for the re- 75 ception of the bolt 32. A forked member 33 engages the upper and lower surfaces of the projection 31, said forked portions having holes therethrough, for the reception of the bolt 32. The member 33 has the stool, or 80 seat member 34 secured thereon.

The lower end of the member 30 has a piece of resilient material 35, such as rubber, secured thereto, which is adapted to press against the member 10, when weight is 85 applied to the stool or seat portion 35.

A spring member 36 is secured to the portion 21, and presses against the upper portion of the member 30, and is adapted, normally, to force the lower portion of the member 30 out of engagement with the base member 10. This is done in order to prevent my 90 device from interfering with the normal operation of the barber chair.

In Figure 3, there is shown in dotted lines, 95 the position the stool or seat member 34 will occupy when not in use, being entirely underneath the barber chair, and in no way interfere with the barber, who is using the 100 chair.

It will thus be seen that I have provided an attachment for barber chairs, which will enable the barber to remain seated in close proximity to the chair, when not employed, and with slight modifications, I desire it to 105 be understood that the use of my device is not to be limited to barber chairs, nor is it to be limited to be used by the barber only when not employed, but may also be used when desired, by the barber while employed 110 in waiting on a customer.

In the description, I have set forth a pre-

ferred embodiment of my invention, and I desire it to be understood that, although specific terms are employed, they are used in a generic and descriptive sense only, and not for purposes of limitation, the scope of the invention being set forth in the appended claims.

I claim:

1. In a chair, a base portion, a seat portion, a member secured to the seat portion, a pivoted arm secured to the first named member, a stool member secured to the pivoted arm, the lower end of the pivoted arm being adapted to rest against the base portion when pressure is applied to the stool member, and means for normally holding said lower end of the pivoted arm out of engagement with the base portion.
2. In an attachable seat for barber chairs and the like, a base portion for the barber chair, a seat portion, a clamp member adapt-

ed to be secured to the lower side of the seat portion, a vertically disposed member pivotally connected to the clamp member, a seat member mounted for horizontal movement 25 on the vertically disposed pivoted member, and a spring for normally holding the vertically disposed member out of engagement with the base portion.

3. In a stool adapted to be attached to 30 barber chairs and the like, a vertically disposed member mounted on a horizontal pivot, said horizontal pivot member being secured to the rim of the seat portion of the chair, a stool mounted on a vertically disposed pivot in the vertically disposed member, said stool being adapted to swing in a horizontal plane beneath the chair when not in use.

In testimony whereof I affix my signature.

JOHN L. SMITH.
